UNITED STATES PATENT OFFICE.

JOHN R. EVANS, OF WINDSOR, ONTARIO, CANADA, ASSIGNOR OF ONE-FOURTH TO
BENJAMIN W. TANZY, OF DETROIT, MICHIGAN.

STEAM GENERATOR.

Application filed April 10, 1924. Serial No. 705,423.

My invention relates to an improvement in steam and hot water generators shown in the accompanying drawings and more particularly described in the following specification and claims.

One of the objects of this invention is to provide a simple and inexpensively constructed furnace and steam generator adapted to readily convert water into steam for heating or power purposes, which is adapted to minimize and eliminate the possibility of explosion and which may be employed as a hot water heater if desired.

A further object of the invention is to provide an apparatus economical in fuel consumption in which steam may be rapidly generated and superheated,—the construction being such that the water delivered from the main may be preheated before entering the coils in which steam is generated.

A further object of the invention is to provide a construction in which the heating coils may be readily and quickly removed for repairs when necessary without seriously hampering its service when repairs are required.

One feature of the invention consists in a plurality of vertically disposed inclined heating coils connected at their lower ends with a manifold from which a steam pipe leads to the heating system, the condensation from the radiators or heating system being returned by gravity to a tank elevated above the boiler;—the condensation passing by gravity from the tank to an upper manifold connected through a plurality of valve controlled "sight feed" tubes with the upper ends of the respective heating coils contained within the walls of the furnace.

Another feature of the invention consists in providing the furnace with a divided or sectional "front" which may be readily detached as required, whereby the several vertical coils contained within the furnace may be easily and quickly removed for repairs when necessary.

Another feature of the invention consists in providing a plurality of "sight feed" tubes in line with nipples or "feed" pipes extending from the upper manifold to the coils whereby the condensation delivered to the heating coils may be observed and regulated.

With the foregoing and other objects in view which will appear as the description 55 proceeds the invention further resides in the combination and arrangement of parts and in the details of construction hereinafter described and claimed it being understood that changes may be made in the precise embodiment of the invention herein disclosed without departing from the spirit of the same.

In the drawings accompanying this specification:

Figure 1 is a front elevation of the furnace showing fragmentary sections of two floors of a building with radiators connected by return pipes to an elevated tank from which the condensation is delivered to an upper manifold and thence to the coils of 70 the furnace.

Figure 2 is a vertical cross-sectional view through the furnace showing the piping system connecting the furnace with the radiators of two floors of a building and from the radiators to an elevated tank from which the condensation is delivered by gravity 75 back to the heating coils in the furnace.

Figure 3 is a rear elevation of the furnace with a pipe connection leading from the 80 lower manifold to the radiators of two floors of a building also a pipe connection leading from said manifold to a tank elevated above the boiler from which the condensation passes by gravity to the heating coils.

Figure 4 is a detail sectional view showing the "sight feed" glass tubes through which the condensation passes from the upper manifold to the respective heating coils.

Figure 5 is an elevation of one of the 90 heating coils.

Referring now to the letters of reference placed upon the drawings:

A denotes a furnace and A¹ indicates the smoke stack leading from the furnace.

B represents the divided front wall of the furnace formed in section b, bolted at b¹ to the frame that ready access may be obtained to the interior of the furnace for the purpose of removing and replacing a 100 plurality of coils housed therein.

C designates a furnace door of usual construction and D an ash pit door.

E denotes the usual grate bars.

F indicates a pipe leading from the water 105 main under control of a valve F^a—to a T-

fitting F^b from which branch pipes F^c are connected with vertically disposed sets of preheating coils G coupled to the manifold H above the top of the furnace.

- 5 I represents a plurality of sets of vertically disposed water heating coils laterally spaced and respectively connected at their lower ends with the manifold J , located adjacent the rear walls of the furnace. The 10 upper ends of the coils extend through the front wall of the furnace and are engaged by nipples L , connected with "sight feed" glass tubes K , in turn connected to the upper manifold H by a plurality of nipples L^1 .
 15 K^a designates valves controlling the delivery of water through the "sight feed" tubes. K^b denotes a nozzle through which the water is allowed to drip or flow in a relatively small stream down through the "sight feed" 20 tubes to the respective heating coils.
 20 M indicates a supporting bracket provided with pipe fittings M^1 above and below for the passage of water from the manifold through the nipples connecting the "sight feed" 25 tubes to the respective coils.

It will be noted that the supporting bracket M is diagrammatically indicated in Figure 4, it being evident that any suitable device may be employed which will serve 30 as a connecting support for the respective pipe ends.

Horizontally interposed between the water heating coils I , are a plurality of baffle plates N , serving to divert the hot gases back and forth over the heating coils.

40 O represents a steam pipe leading from the lower manifold J ,—controlled by a valve O^a ,—extending upwardly through the several floors and connected with the radiators P . P^a designates shut-off valves adapted to 45 cut off the delivery of steam to the respective radiators.

R denotes a return pipe connected with the respective radiators P through which 45 the condensation or steam is returned to a tank S suitably elevated above the top of the boiler. S^a indicates a gauge glass for determining the level of condensation in the tank.

50 T represents a pipe for delivering the condensation from the tank S , to the upper manifold H , from which it passes to the "sight feed" tubes K , and thence to the coils I .

55 U designates a pipe leading from the lower manifold J to the tank S , and is fitted with a trap U^a and a valve U^b controlling the passage of condensation to the tank. U^c denotes a pipe leading from the trap U^a to a sewer or other point of discharge, controlled by a valve U^d .

60 V indicates a pressure gauge connected by a pipe V^a with the lower manifold J .

65 W represents a pipe leading from a T-shaped fitting connected with the lower manifold to a suitable blow-off or relief

valve W^a , thereby providing against excessive pressure.

Having now indicated the several parts by reference letters the construction and operation of the device will be readily understood. 70

Water is primarily admitted to the heating coils,—or when necessary to replenish same—from a water main through the valve F^a to the coils G , upon opening the valve F^a . The water is here preheated before 75 delivery to the upper manifold H , from which it passes to the respective "sight feed" tubes K , where its "feed" is controlled by the valves K^a , and thence to the heating coils I , where it is rapidly converted into steam 80 as the water flows down the coils toward the body of the fuel supported upon the grate bars. The steam passes into the lower manifold J and is carried by the pipe O upwardly to the several radiators P on the 85 respective floors of the building,—the condensation from the radiators flowing by gravity back through the pipe R to the tank S located above the furnace. From this tank the condensation passes through the 90 pipe T to the upper manifold H where it is again delivered to the heating coils I through the "sight feed" tubes K in the manner previously described.

Should condensation form in the lower 95 manifold or be held in the trap U^a it may be discharged into the elevated tank S upon opening the valve U^b and closing the valve O^a , the steam thus forcing the water of condensation upwardly through the pipe U to the elevated tank. Upon the condensation being forced into the tank the valve U^b may be again closed and the valve O^a opened.

If desired the condensation in the trap 100 and lower manifold may be discharged into the sewer through the pipe U^c upon opening the valve U^d . Should the stem pressure become excessive it will be relieved through the blow-off valve W^a .

Should it become necessary to remove any 105 of the coils for repairs a section of the furnace front may be removed whereupon the defective coil may be removed, repaired and replaced.

Having thus described my invention what 110 I claim is:

1. In an apparatus of the character described, a plurality of laterally spaced sets of vertically disposed steam generating coils, a manifold connected with the lower ends of said coils, vertically disposed pre-heating water coils arranged in spaced relation with the steam generating coils and adapted for connection with a water main and having inlet ends at the bottom of the apparatus, an elevated manifold connected with the pre-heating water coils and with the upper ends of the steam generating coils, a plurality of sight feed tubes respectively in line with the several steam generating coils 120
2. In an apparatus of the character described, a plurality of laterally spaced sets of vertically disposed steam generating coils, a manifold connected with the lower ends of said coils, vertically disposed pre-heating water coils arranged in spaced relation with the steam generating coils and adapted for connection with a water main and having inlet ends at the bottom of the apparatus, an elevated manifold connected with the pre-heating water coils and with the upper ends of the steam generating coils, a plurality of sight feed tubes respectively in line with the several steam generating coils 125
3. In an apparatus of the character described, a plurality of laterally spaced sets of vertically disposed steam generating coils, a manifold connected with the lower ends of said coils, vertically disposed pre-heating water coils arranged in spaced relation with the steam generating coils and adapted for connection with a water main and having inlet ends at the bottom of the apparatus, an elevated manifold connected with the pre-heating water coils and with the upper ends of the steam generating coils, a plurality of sight feed tubes respectively in line with the several steam generating coils 130

and their connection with the upper manifold, and valves for regulating the "flow" through said sight feed tubes.

2. In an apparatus of the character described, a plurality of vertically disposed steam generating coils, a plurality of horizontally disposed baffle plates between the loops of said coils, a manifold connected with the lower ends of the coils, vertically disposed pre-heating water coils adapted for connection with a water main, an elevated manifold connected with the pre-heating water coils and with the upper ends of the steam generating coils, means for regulating the flow from the upper manifold through the steam generating coils, a steam pipe connected to the lower manifold, a valve governing the steam passage through said pipe, a receiving tank elevated above the upper manifold, a return pipe between the receiving tank and the upper manifold, a pipe connection fitted with a trap between the lower manifold and the receiving tank and a valve in said pipe connection controlling the passage from the lower manifold to the receiving tank.
3. In an apparatus of the character described, a plurality of vertically disposed steam generating coils, a sectional front for said apparatus adapted to be detached for the removal or replacement of the coils, a

manifold connected with the lower end of the coils adjacent to the outer wall of the apparatus, vertically disposed preheating water coils housed within the walls of the apparatus adapted for connection with a water main, a manifold elevated above the top of the apparatus connected with the preheating water coils and with the upper ends of the steam generating coils, a plurality of sight feed tubes respectively in line with the several steam generating coils and their connections with the upper manifold, a plurality of valves for regulating the passage through said sight feed tubes, a steam connection between the lower manifold and the heating system, a valve controlling said steam connection, a receiving tank elevated above the upper manifold, a return pipe leading from the heating system to the receiving tank, a pipe connecting the receiving tank with the upper manifold, a pipe connection fitted with a trap between the lower manifold and the receiving tank having a valve to govern the passage, a valve controlled pipe leading from said trap to a sewer or other place of discharge and a blow-off valve to relieve the apparatus of excessive pressure.

In testimony whereof, I sign this specification.

JOHN R. EVANS.
